UNITED STATES PATENT OFFICE.

HAROLD KELLY, OF BIDDEFORD, MAINE, ASSIGNOR OF ONE-HALF TO JOHN P. KELLY, OF SACO, MAINE.

LEASE-ROD.

SPECIFICATION forming part of Letters Patent No. 624,658, dated May 9, 1899.

Application filed January 26, 1899. Serial No. 703,413. (No model.)

To all whom it may concern:

Be it known that I, HAROLD KELLY, a citizen of the United States, residing at Biddeford, in the county of York and State of Maine, have invented certain new and useful Improvements in Lease-Rods; and I do hereby declare the following to be a full, clear, and exact description of the invention, such as will enable others skilled in the art to which it appertains to make and use the same.

My invention relates to improvements in lease-rods, and the same is illustrated in the accompanying drawings, in which—

Figure 1 is a perspective view of so much of a loom as is necessary to show the application of my improved rods thereto. Figs. 2 and 4 are an elevation and cross-section, respectively, of a lease-rod. Figs. 3 and 5 are an elevation and cross-section, respectively, of a different form or shape of lease-rod. Fig. 6 is a sectional view of the adjustable rod-holder, and Fig. 7 is an end view of the holder.

Same letters of reference refer to like parts.

The warp-threads when they leave the beam are frequently stuck together by reason of the sizing or interlocking of fibers or knots in the thread, and when separated by the usual lease-rod threads are in consequence often broken, causing much delay and imperfection in the woven goods.

The object of my invention is to obviate these difficulties.

In said drawings, A represents the frame of a loom; B, the beam; C, the whip-roll, and D the warp.

My invention relates particularly to that one of the lease-rods nearest the beam.

It consists in a rotatable rod.

It further consists in means for imparting a rotary motion to said rod.

It further consists in means adapted to render the rod quickly and easily mounted in and dismounted from its supports.

To these ends I secure to either side of the frame upright standards E, with suitable horizontal bearings F at the top. Mounted in said horizontal bearings are shafts G, having on the ends thereof socketed holders H, adapted to receive and support the ends of the rod. Said rod may be rotated in any con-

venient manner—as, for example, by a belt I, passing over a pulley J on shaft G and a pulley K on shaft L.

It is important that the rod may be quickly and easily inserted and removed from the warp. I therefore make one of the supporting-shafts capable of longitudinal movement sufficient to release the end of the rod from the socket in the holder. This construction I have illustrated in Figs. 1 and 7. The shaft G is held yieldingly by means of a coil-spring U, interposed between the bearing F and the head of the rotary shaft which supports the rod.

To facilitate the separation of the warp-threads from each other, the rod is made of such a shape that the rotation thereof periodically increases and diminishes the distance between the warp-threads according as a line extending from the points of contact of the upper and lower threads on the rod passes through a longer or shorter dimension of the rod. The rod may therefore be of any shape in cross-section except circular. The shapes shown in Figs. 3 and 4 are examples in which the longer and shorter dimensions are marked.

It will be evident that the cross-sectional shape of the rod may be indefinitely varied without departing from the spirit of my invention. The supports which carry the rotatable holders can be adjusted vertically by moving the standards up or down in tubular brackets S, secured to the sides of the frame, and may be held in any desired position by set-screws T, thus increasing or diminishing the tension on the warp. It will also be evident that the manner of supporting the rod and the means for imparting a rotary motion to the rod may be varied at will without departing from the spirit of my invention, the leading feature of which is the rotation of the rod next the beam, said rod having unequal diameters.

The operation of my improved lease-rod is as follows: The warp-threads constantly under tension pass from the beam over the whip-roll and thence alternately over and under the first rod and under and over the second rod. The rotation of the rod changes the angle between the upper and lower threads on

the whip-roll side, and likewise the tension, thereby more gradually separating the threads and rendering them less liable to be broken.

Having thus described my invention and its

use, I claim—

1. In a loom, a lease-rod, means for supporting said rod independently of the warp-threads and means for imparting a rotary motion to said rod.
2. In a loom, rotatable holders, a lease-rod mounted therein, one holder being held yieldingly against longitudinal movement and means for rotating said rod.
3. In a loom, rotatable holders, a lease-rod supported therein, means for rotating said holders and rod, said rod having diameters of varying length.

4. In a loom, rotatable holders adjustable vertically, a lease-rod supported in said holders and means for rotating said holders and rod.

5. In a loom, rotatable holders having sockets in their adjacent ends, a lease-rod adapted to have its ends supported in said sockets of said holders and means for imparting a rotary motion to said holders and rod.

In testimony whereof I affix my signature, in presence of two witnesses, this 19th day of January, 1899.

HAROLD KELLY.
